UNITED STATES PATENT OFFICE.

HENRY E. BARNEY, OF DEAN, OHIO.

DESIGN FOR A WATER-MIXING STAND FOR CREAM-SEPARATORS.

SPECIFICATION forming part of Design No. 31,640, dated October 10, 1899.

Application filed September 16, 1899. Serial No. 730,776. Term of patent 7 years

To all whom it may concern:

Be it known that I, HENRY E. BARNEY, of Dean, in the county of Montgomery and State of Ohio, have produced a new and original Design for a Water-Mixing Stand for Cream-Separators, of which the following is a specification, reference being had to the accompanying drawings, forming part thereof, in which like letters refer to like parts.

10 In the drawings, Figure 1 represents a side elevation of a water-mixing stand for a cream-separator embodying my design. Fig. 2 is a vertical sectional view thereof. Fig. 3 is a bottom plan view of the same, and Fig. 4 is a

15 sectional top plan view on line X X of Fig. 1.

The leading or essential feature of my design consists of a hollow cylindrical perforated column surmounted by a conical top, said cylindrical column terminating at its base in a

20 projecting annular perforated flange.

In said drawings, *a* represents a hollow cylindrical column or tube formed with small perforations *b* throughout substantially its entire length. *c* is a conical top of said column formed with a rib *d* near its top. *e* represents a projecting concavo-convex perforated flange at the base terminal of said cylindrical column and having at its bottom a series of short projections *g*.

25 What I claim is—

30 The design for a water-mixing stand for a cream-separator, substantially as described.

In witness whereof I have hereunto set my hand this 5th day of June, 1899.

HENRY E. BARNEY.

Witnesses:

F. M. BURNHAM,
H. M. WALSH.
